UNITED STATES PATENT OFFICE.

JOHN CHARLIE KING, OF DALBY, QUEENSLAND, AUSTRALIA.

DESIGN FOR A TAG-HOLDER.

51,386.

Specification for Design.

Patented Oct. 16, 1917.

Application filed July 1, 1916. Serial No. 107,200. Term of patent 14 years.

To all whom it may concern:

Be it known that I, JOHN C. KING, a subject of the King of Great Britain, residing at Dalby, Queensland, Australia, have invented a new, original, and ornamental Design for Tag-Holders, of which the following is a specification, reference being had to the accompanying drawing, forming a part thereof.

Figure 1 is a perspective view of one side;

Fig. 2 is a perspective view of the opposite side; and

Fig. 3 is a top plan view of a tag holder, showing my new design.

I claim:

The ornamental design for a tag holder, as shown.

JOHN CHARLIE KING.
